HYDRAULIC TORQUE CYLINDER

Wayne W. McMullen, 1002 67th St., and Leo S. Goulsen,
1065 67th St., both of Des Moines, Iowa
Filed July 17, 1962, Ser. No. 210,376
9 Claims. (Cl. 280—43.17)

Creating torque through the linear displacement of a power component has been used in various equipment in the field of mechanics heretofore. Thus is the principle of the rack and pinion. However, these devices are generally cumbersome to operate and do not provide a high mechanical efficiency.

Therefore, the principal object of our invention is to provide a hydraulic torque cylinder which can impart torque to a related shaft by the linear displacement of a piston and rod within the cylinder.

A further object of our invention is to provide a hydraulic torque cylinder which has a high mechanical efficiency.

A still further object of our invention is to provide a hydraulic torque cylinder which can simultaneously impart torque to shafts mounted within opposite ends of the cylinder.

A still further object of our invention is to provide a hydraulic torque cylinder which can simultaneously impart torque to shafts mounted within opposite ends of the cylinder wherein the shafts will turn in opposite directions.

A still further object of our invention is to provide a hydraulic torque cylinder which can simultaneously impart torque to shafts mounted within opposite ends of the cylinder wherein the shafts will turn at different speeds in opposite directions.

A still further object of our invention is to provide a hydraulic torque cylinder which can be secured to a vehicle having crank shaft wheel supporting axle elements whereby the rotation of the crank shaft elements will result in vertical displacement of the vehicle.

A still further object of our invention is to provide a hydraulic torque cylinder which is self-locking.

A still further object of our invention is to provide a hydraulic torque cylinder which is economical of manufacture, durable in use and refined in appearance.

These and other objects will be apparent to those skilled in the art.

Our invention consists in the construction, arrangements, and combination, of the various parts of the device, whereby the objects contemplated are attained as hereinafter more fully set forth, specifically pointed out in our claims, and illustrated in the accompanying drawings, in which:

FIGURE 1 is a longitudinal sectional view of our device when the piston and piston rod are half way between their positions of maximum displacement in two opposite directions;

FIGURE 2 is a sectional view of our device which is taken at right angles to the sectional view in FIGURE 1;

FIGURE 3 is a rearward elevational view of our device mounted on a vehicle having crankshaft-type axles;

FIGURE 4 shows two side elevational views of the vehicle shown in FIGURE 3; one view showing the vehicle in an elevated position, and the other view showing the vehicle in a lowered condition;

FIGURE 5 is a perspective view of a different form of our device;

FIGURE 6 is a schematic view showing the interrelated components of one end of our cylinder device; and

FIGURE 7 is a schematic view of the hydraulic circuitry which controls our cylinder device.

We have used the numeral 10 to generally designate a hollow center cylinder which has its opposite ends jour-

2

naled in cylindrically shaped casings 12 and 14. Cylinder 10 is secured to casings 12 and 14 by weldments 16. The outer ends of casings 12 and 14 terminate in shoulders 18 which have center openings 20 and 22, respectively. 5 As shown in FIGURE 3, brackets 24 extend from the outer ends of casings 12 and 14 to effect a rigid connection to the bottom of horizontal vehicle frame 26 by means of bolts 28.

An inner cylindrical casing 30 is positioned within casing 14. A bearing 34 is rigidly positioned in either end of cylinder 10 and a collar 36 extends outwardly therefrom to terminate adjacent the inner ends of each of the inner casings 30 and 32. A weldment 38 rigidly secures the bearings 34 to the cylinder 10. Sealing rings 40 in the outer periphery of bearings 34 serve to seal the interior of cylinder 10. A conventional thrust bearing 42 comprised of bearing ring 44 and outwardly extending collar 46 is movably mounted within the collar 36 of each of the bearings 34. Collars 46 are received within 15 the inner ends of casings 30 and 32 and are welded to these casings as shown in FIGURES 1 and 2. Stud shafts 48 are rigidly secured to and extend outwardly from the outer ends of casings 30 and 32 and are received in the center bores 50 of shafts or axles 52 and 54 which have 20 their inner ends rotatably mounted in center openings 20 and 22 of casings 12 and 14, respectively. Pins 56 extend through each of the respective pairs of stud shafts and axles to effect this rigid connection therebetween. A thrust bearing 58 separates the inner surface of the outer 25 ends of outer casings 12 and 14 from the outer ends of inner casings 30 and 32, respectively.

As shown in FIGURE 1, conduits 60 and 62 appear in bearings 34 at the ends of cylinder 10 and terminate in ports 64 and 66, respectively. A piston 68 is slidably 35 mounted within cylinder 10 and rods 70 and 72 extend outwardly from opposite sides thereof. Rods 70 and 72 extend through the bearings 34 and thrust bearings 42 on opposite ends of cylinder 10, and thence into the interiors of inner casings 30 and 32, respectively. A sealing ring 74 on the periphery of the center bore 76 in bearings 34 serve to seal the interior of the cylinder 10. Pins or shafts 78 and 80 extend transversely through the opposite ends of rods 72 and 74, respectively. Pins 78 and 80 dwell in the same plane with each other. Pairs of 40 straight horizontal elongated slots 82 appear in outer casing 12 and a similar pair of slots 84 appear in casing 14. Slots 82 are in alignment with slots 84. Pairs of oppositely disposed spirally shaped arcuate slots 86 appear in inner casing 30 and a similar pair of slots 88 appear in inner casing 32. The ends of pin 78 are received within pairs of slots 82 and 86 in casings 30 and 32, respectively, and roller bearings 90 on pin 78 movably engage these pairs of slots. Similarly, the ends of pin 80 are received within the pairs of slots 84 and 88, and roller 45 bearings 92 on pin 80 movably engage these pairs of slots. The center axis of arcuate slots 86 and 88 follow a uniform spiral except at the extreme ends thereof wherein the spiral axis is reversed to terminate in arcuate notches 94 which are adapted to receive the roller bearings 90 or 92 at times. The slots 86 and 88 extend approximately one-fourth of the way around the respective inner casings 30 and 32.

As shown in FIGURES 3, 6 and 7, axles 52 and 54 are comprised of a first horizontal portion 96, a center vertical portion 98, and a second horizontal portion 100 wherein the L-shape of one end of a conventional crankshaft is created. Wheels 102 can be secured in conventional fashion to the outer ends of the second 50 horizontal portions 100 of axles 52 and 54. Brackets 104 can embrace the first horizontal portions 96 of the axles to effect the connection of the axles to frame 26.

Conduits 106 and 108 are connected in conventional fashion to ports 64 and 66, respectively, of cylinder 10, and each of these conduits terminate in valve 110 which is capable of directing the flow of hydraulic pressure into one conduit and receiving a discharge of fluid therethrough from the other conduit. The neutral position of the valve shown in FIGURE 7 prevents the flow of fluid in either direction through the valve. Conduits 112 and 114 connect valve 110 with pump 116 and reservoir 118, respectively, and conduit 120 interconnects the pump and the reservoir.

We have shown a different form of our invention in FIGURE 5. All components in this figure are similar to the above described device except for the arcuate slot in inner casing 32 whose counterpart is designated 32A in this figure. The arcuate slot 88A in casing 32A has its spiral axis reversed with respect to slot 86 in casing 30. Also, the length and pitch of slot 88A is slightly greater than that of slot 86. As will be described hereafter, this will serve to cause one shaft to rotate at a different speed than the other shaft. It will be noted that the transverse pins 78 and 80 in FIGURE 5 have been positioned substantially apart although this requirement can be varied as the length and pitch of slot 88A is varied. The straight slots 82 and 84 must also be positioned accordingly to accommodate this new position of pins 78 and 80.

The normal operation of our device is as follows: With the piston 68 in the position shown in FIGURES 1 and 2, the valve 110 can be actuated to permit the pump 116 to force fluid through conduits 112 and 106 into port 64 and conduit 60 of cylinder 10. Fluid on the other side of piston 68 will then be forced out of conduit 62 and port 66, thence into conduit 108 and valve 110, and thence through conduit 114 into reservoir 118.

This movement of fluid will cause piston 68 to move to the left as viewed in FIGURES 1 and 2. The rods 70 and 72 normally move longitudinally with piston 68 as dictated by the extension of pins 78 and 80 in straight slots 82 and 84, which are located in the rigidly secured casings 12 and 14. However, the rectilinear movement of piston 68, rods 70 and 72, and transverse pins 78 and 80 is resisted by the engagement of the roller bearings 90 and 92 in the arcuate slots 86 and 88, respectively, in the inner casings. The rectilinear movement of the above described components causes the transverse pins 78 and 80 to exert a rotational force on arcuate slots of the inner casings 30 and 32, respectively, as these casings are rotated to permit the rectilinear movement of the pins 78 and 80 to continue. Thus, the pins 78 and 80 induce rotation of the inner casings 30 and 32, respectively, through the rotational force exerted at the arcuate slots thereon by the rectilinear movement of the pins within the arcuate slots. The inner casings must rotate to permit the rectilinear movement of the pins through the arcuate slots in the inner casings. The axles 52 and 54 which are rigidly secured to casings 30 and 32, respectively, will reflect this rotational movement and rotate therewith. Thus, if the vehicle frame 26 were in an elevated position similar to that of the left-hand view in FIGURE 4, it will be lowered to the lower elevation shown in the right hand view in this figure. A reversal of the movement of fluid as described above by valve 110 would obviously reverse this phenomenon. The two views in FIGURE 4 depict the extreme positions of elevation created by the device in FIGURES 1 and 2.

As the roller bearings 90 and 92 move into the locking slots 94 at the ends of the arcuate slots 86 and 88, the weight imposed upon the axles 52 and 54 is imparted to the inner casings 30 and 32, and to the outer casings 12 and 14, which serves to relieve the entire support of the load from the hydraulic system. The roller bearings 90 and 92 will stay in the arcuate shaped locking notches 94 until removed therefrom by a reverse flow of fluid under pressure being exerted against piston 68. The

shape of the notches 94 is complementary to that of the roller bearings 90 and 92.

The device shown in FIGURE 5 operates similarly to the above described unit, except the reversal of the arcuate slot 88A causes the axles 52 and 54 to rotate in opposite directions. This phenomenon would have many applications, and could serve to lower one side of frame 26 and raise the other to create a leveling effect if the frame were supported on sloping terrain. The variance in the length, slope, or pitch of slot 88A as compared to that of slot 86 will cause axle 54 to turn at a different speed than that of axle 52. This phenomenon has many applications in the fields of automation.

It is seen that by varying the length, slope or pitch of the arcuate slots 86 and 88, and changing the positions of pins 78 and 80, and straight slots 82 and 84, innumerable combinations of relative movement between axles 52 and 54 can be created. Thus, our device is seen to accomplish at least all of its stated objectives.

Some changes may be made in the construction and arrangement of our hydraulic torque cylinder without departing from the real spirit and purpose of our invention, and it is our intention to cover by our claims, any modified forms of structure or use of mechanical equivalents which may be reasonably included within their scope.

We claim:

1. In a hydraulic torque cylinder, an elongated cylinder, an outer hollow casing secured to the end of said cylinder, an inner hollow casing movably mounted for rotation about its own longitudinal axis within said outer casing, a shaft means extending through said outer casing and being rigidly secured to said inner casing, at least one straight slot in said outer casing, an arcuate slot disposed on a spiral axis in said inner casing, a piston slidably mounted in said cylinder, a rod protruding from said piston into the interior of said inner and outer casings, a pin extending transversely from said rod and extending into the slots in said inner and outer casings, means for connecting said cylinder to a source of hydraulic power to reciprocate said piston and rod therein at times wherein the reciprocal movement of said rod and the pin secured thereto will impart relative rotational movement between said inner and outer casings, and said arcuate slot is formed with an arcuate locking notch at its ends to retain at times the ends of the pin that extends transversely from said rod.

2. In a hydraulic torque cylinder, an elongated cylinder, first and second hollow outer casings secured to the opposite ends of said cylinder, inner hollow casings movably mounted for rotation about their own respective axes within each of said outer casings, shaft means extending through each of said outer casings and being rigidly secured to one each of said inner casings, straight slots in said outer casings, arcuate slots disposed on a spiral axis in said inner casings, a piston slidably mounted on said cylinder, rods protruding from said piston into the interior of said inner and outer casings on opposite ends of said cylinder, pins extending transversely from said rods and extending into the slots in said inner and outer casings, and means for connecting said cylinder to a source of hydraulic power to reciprocate said piston and rods therein at times wherein the reciprocal movement of

said rods and the pins secured thereto will impart relative rotational movement between the inner and outer casings on the opposite ends of said cylinder.

3. The structure of claim 2 wherein bracket means are secured to said outer casings and are adapted to secure said casings to a frame or the like to hold said casings against movement.

4. The structure of claim 2 wherein said straight and arcuate slots appear in pairs on the respective casings in which they appear.

5. The structure of claim 2 wherein an arcuate locking notch is located at the ends of said arcuate notches to retain at times the ends of the pins that extend transversely from said rods.

6. In combination, a vehicle having a frame, axles comprised of a first horizontal portion, a center straight portion, and thence a second horizontal portion, wheel units on said second horizontal portions, means rotatably securing said first horizontal portions to said frame with the longitudinal axes thereof extending in the same direction, and a hydraulic torque cylinder, comprising,

an elongated cylinder, first and second hollow outer casings secured to the opposite ends of said cylinder, and said outer casings having straight slots,

inner hollow casings movably mounted for rotation about their own respective axes within each of said outer casings, and said inner casings having therein arcuate slots disposed on a spiral axis,

said first horizontal portions of said axles extending through each of said outer casings and being rigidly secured to one each of said inner casings, a piston slidably mounted on said cylinder,

5

rods protruding from said piston into the interior of said inner and outer casings on opposite ends of said cylinder,

pins extending transversely from said rods and extending into the slots in said inner and outer casings, means rigidly securing said outer casings to said frame, a source of hydraulic power on said frame, conduits connecting said source of hydraulic power to said cylinder on opposite sides to said piston, a valve imposed in one of said conduits and being adapted to direct the flow of fluid into and out of said cylinder to move said piston and said rods to impart rotational motion to said inner casings and said axles.

10

7. The structure of claim 6 wherein an arcuate locking notch is located at the ends of said arcuate slots to retain at times the ends of the shafts that extend transversely from said rods.

15

8. The structure of claim 6 wherein said arcuate slots define the same longitudinal axes.

9. The structure of claim 6 wherein said arcuate slots define different longitudinal axes.
